UNITED STATES PATENT OFFICE

WILLIAM D. WRIGHT, OF BROCKPORT, NEW YORK

HOT CAP APPLIER FOR PLANTS

Application filed October 8, 1930. Serial No. 487,199.

The present invention relates to hot cap applicers for plants and an object thereof is to provide a novel means of effectively covering with dirt the outwardly extending flange at the base of the cap. Another object of the invention is to provide for leveling the base flange of the cap prior to covering the same with dirt. Still another object of the invention is to provide for holding the caps in position on the applying member.

To these and other ends, the invention consists of certain parts and combinations of parts all of which will be hereinafter described; the novel features being pointed out in the appended claims.

In the drawings:

Fig. 1 is a plan view of one embodiment of the invention;

Fig. 2 is a view in side elevation of said embodiment;

Fig. 3 is a vertical section through such embodiment;

Fig. 4 is a plan view of another embodiment;

Fig. 5 is a view in side elevation of the embodiment shown in Fig. 4;

Fig. 6 is a fragmentary vertical section of the embodiment shown in Fig. 4; and

Fig. 7 is a detail view of the leveling device.

In the embodiment of the invention shown in Figs. 1 to 3 inclusive, there is employed a cap applying device 1 in the form of an inverted cup shaped member at the end of a shaft 2, which, in this instance, is of hollow formation. This cup shaped applying member receives a hot cap 3 made of paper treated to make it transparent and having an outwardly extending flange 4 at its edge project-

ing beyond the edge of the applying cup 1 and engaged on its upper surface by fingers 5 projected horizontally from the edge of the cup 1. The cap is introduced into the cut and the whole is then applied over the plant to be protected, the flange of the cap being brought against the upper surface of the soil about the plant.

If desired, a cap holding means may be associated with the applying cup, to hold the cap therein. In this embodiment, the cap

holding means is in the form of a suction means arranged in the hollow shaft 2 to create suction on the cap at its crown point. The hollow shaft 2 forms a cylinder in which a piston 6 operates, the lower end of the cylinder being open to the cup and the upper end being closed at 7 except for a small opening through which a piston rod 8 is connected with the cylinder and extends to a handle 9 above the upper end of the shaft. A spring 10 acts on the rod 8 and the shaft 2 to hold the rod in its lower position. When a handle 11 on the shaft 2 is grasped to control the cup applicer, the handle 9 may be grasped to create a suction on the cap at the crown point to hold the cap while the latter is being applied over the plant.

Associated with the cap applicer is a means for covering the flange of the cap with dirt. This means, in this instance, comprises a plurality of plows 12 which are carried eccentrically by a shaft 13, which, in this instance, is also of hollow formation and surrounds the shaft 2, being supported therefrom by arms 14 extending downwardly and outwardly from the lower end of the shaft 13 and connected to a ring 15 to which the brackets 16 on the plows 12 are connected. A spring 17 arranged between the lower end of the shaft 13 and a brace 17^a between the shaft 2 and the cup 1 acts to hold the plows in an elevated position while the cap is being applied to the plant. After the cap is applied, the plows are, through the handle 18 on the upper end of shaft 13, forced downwardly into the soil and then turned. The plows are so formed that they throw the soil toward the axis of the shaft 13 and over the flange 5 of the cup.

With the purpose in view of insuring the leveling of the cap flange before the dirt is thrown therein, leveling means is provided comprising, in this instance, rollers 19 mounted to turn on short shafts 20 at oblique angles to the horizontal and supported by brackets 21 secured to the ring 15 so that the rollers travel over the flange slightly in advance of the plows and flatten or level the flange 4 just before the dirt is thrown thereon by the plows.

In the embodiment shown in Figs. 4 to 7 inclusive, the cap applicer comprises a ring 22 supported by arms 23 from the lower end of a hollow shaft 24 which has a handle 25 at the upper end of said shaft. The cap is received in this applicer and when applied over a plant the ring acts to press the flange of the cap against the soil.

A holding means may be provided to hold 10 the cap in the applicer to release it at will. In this instance, the holding means embodies a pair of spring arms 26 lying in the hollow shaft 24 and having pointed ends 27 adapted to pass through the lower end of the shaft 15 to engage a cap in the applying member. These arms having overlapping deflected portions 28 between their ends and on these deflected portions operates a ring 29 which may be moved up and down in the hollow 20 shaft 24 by means of a rod 30 extending upwardly in the hollow shaft to a hand piece 31 above the upper end of the shaft. When moved in one direction the jaws open, and when moved in the other direction the jaws 25 close. When closing the jaws will pass below the lower end of the shaft and grip a cap at its crown, and when opening they pass into the shaft and the cap is stripped therefrom by the end of the shaft and released.

30. The covering means for the flange of the cap, in this latter embodiment comprises two plows 32 supported by bracket arms 33 which adjustably connect at 34 by bolts and slots with the arms 23.

35. In this embodiment the cap applicer as well as the plows are turned and this causes the plows to throw the soil inwardly toward the axis of the shaft 24 and over the flange of the cap projecting beyond the ring 22.

40. The leveling or flattening of the flange may be effected by leveling fingers 35 projecting outwardly from the ring 22 in advance of the plows so that the flange of the cap is flattened just prior to the soil being turned thereover 45 by a plow.

In both embodiments of the invention, a cap applicer is provided having releasable means for holding a cap therein until the cap is positioned over a plant. This releasable 50 means is mounted in the shaft to which the applicer is secured and cooperates with the cap at the crown point thereon. Plows are provided which turn the soil over the flange on the hot cap after the latter has been applied 55 over a plant. The plows are carried eccentrically by a shaft which, when turned, causes the soil to be moved toward the axis of turning of the shaft. In advance of the plows operate leveling means which moves the 60 flange of the cap to a position where it will be effectively covered by the soil thrown inwardly by the plows.

What I claim as my invention and desire to secure by Letters Patent is:

65. 1. The combination with a shaft, and a

plow arranged eccentrically to the axis of the shaft, so that when the shaft is turned about its axis the plow will throw dirt inwardly toward the axis of the shaft, of a hot cap applicer for applying a hot cap in line 70 with the shaft so that a flange edge on the latter may be covered by the plow on the turning of the shaft.

2. The combination with a shaft, and a plow arranged eccentrically to the axis of 75 the shaft, so that when the shaft is turned about its axis the plow will throw dirt inwardly toward the axis of the shaft, of a hot cap applicer for applying a hot cap in line 80 with the shaft so that a flange edge on the latter may be covered by the plow on the turning of the shaft, and a cap flange leveler mounted eccentrically on the shaft in advance of the plow.

3. The combination with a hollow shaft, 85 and a plow arranged eccentrically to the axis of the shaft, so that when the shaft is turned about its axis, the plow will throw dirt inwardly toward the axis of the shaft, of a hot 90 cap applicer, a second shaft mounted in the first named shaft in a line with both shafts in a position to apply a hot cap over a plant and position a flange on the cap in a position to be covered by earth thrown inwardly 95 by the plow.

4. The combination with two shafts arranged one within the other, a cup shaped 100 hot cap applied arranged on one end of the inner shaft in line with the latter, and a plow supported eccentrically by the outer shaft beyond the hot cap applicer and having a surface so disposed as to throw dirt toward the hot cap applicer as the shaft of the plow is turned relatively to the shaft of the hot cap applicer.

5. The combination with two shafts 105 arranged one within the other, a cup shaped hot cap applicer arranged on one end of the inner shaft in line with the latter, and a plow supported eccentrically by the outer shaft beyond the hot cap applicer and having a surface 110 so disposed as to throw dirt toward the hot cap applicer as the shaft of the plow is turned relatively to the shaft of the hot cap applicer, and a cap flange leveler carried by the outer shaft in advance of the plow.

6. The combination with a cup shaped hot 115 cap applicer, a plow, and means supporting said plow for travel about the hot cap applicer to cause said plow to throw dirt inwardly over the flange of a hot cap being applied by said applicer.

7. The combination with a cup shaped hot 120 cap applicer, a plow, and means supporting said plow for travel about the hot cap applicer to cause said plow to throw dirt inwardly 125 over the flange of a hot cap being applied by said applicer, and a flange level also supported by said means in advance of the plow.

8. The combination with a hot cap applicer, of a plow supported by said applicer on the 130

outer side thereof to turn with the applier in order to throw dirt inwardly on the flange of a hot cap being applied by the applier.

9. The combination with a hot cap applier, of a plow supported by said applier on the outer side thereof to turn with the applier in order to throw dirt inwardly on the flange of a hot cap being applied by the applier, and a flange leveler supported by and on the outside of the applier in advance of the plow.

10. The combination with a hot cap applier, of movable releasable means subject to the control of the operative for holding a hot cap to the applier.

11. The combination with an inverted cup shaped hot cap applier, of movable releasable means arranged to cooperate with the crown of a hot cap in said applier.

12. The combination with an inverted cup shaped hot cap applier, of releasable means arranged to cooperate with the crown of a hot cap in said applier, said releasable means being a movable suction creating device.

13. The combination with an inverted cup shaped hot cap applier, of releasable means arranged to cooperate with the crown of a hot cap in said applier, said releasable means being a grip device arranged at the crown of the cup shaped applier.

14. The combination with a hollow shaft, and a hot cap applier arranged at one end of the shaft, of a cap holding means operable in said hollow shaft for engaging the crown of a hot cap in the applier.

15. The combination with a hot cap applier having a handle extending upwardly therefrom, of releasable means for holding a hot cap to the applier, and controlling means for the releasable means mounted on the handle and subject to the control of an operative from a point above said hot cap applier.

16. The combination with an inverted cup shaped hot cap applier having a handle projecting upwardly therefrom, and a device for creating a suction in the cap applier mounted on the handle.

17. The combination with an inverted cup shaped hot cap applier, of a handle arranged above the same, holding means for holding a cap in the applier, and manually operable means for effecting a control of the releasing means controllable from the handle.

WILLIAM D. WRIGHT.
